CLAIM

The ornamental design for a wearable interactive device, design as shown and described.

DESCRIPTION

FIG. 1 is a perspective view of a wearable interactive device. FIG. 2 is a front view of the wearable interactive device. FIG. 3 is a rear view of the wearable interactive device. FIG. 4 is a left side view of the wearable interactive device. FIG. 5 is a right side view of the wearable interactive device. FIG. 6 is a top view of the wearable interactive device; and, FIG. 7 is a bottom view of the wearable interactive device.
